UNITED STATES PATENT OFFICE

GERTRUDE H. CRAWFORD, OF MILLIKEN, COLORADO

DESIGN FOR A PASTRY CONFECTION

Application filed December 9, 1932. Serial No. 46,406. Term of patent 14 years.

To all whom it may concern:

Be it known that I, GERTRUDE H. CRAWFORD, a citizen of the United States, residing at Milliken, in the county of Weld and State of Colorado, have invented a new, original, and ornamental Design for a Pastry Confection, of which the following is a specification, reference being had to the accompanying drawing, forming part thereof.

Fig. 1 is a plan view of a pastry confection, showing my new design; and

Fig. 2 is a side view of the confection.

I claim:

The ornamental design for a pastry confection, as shown.

In testimony whereof I affix my signature.

GERTRUDE H. CRAWFORD.
